H. N. JOSLEYN & J. W. KOERNER.

TYPE WRITING MACHINE.

APPLICATION FILED APR. 6, 1915.

1,206,854.

Patented Dec. 5, 1916.

FIG. 3.

UNITED STATES PATENT OFFICE.

HUBBARD N. JOSLEYN AND JOHN W. KOERNER, OF SYRACUSE, NEW YORK, ASSIGNEES,
BY MESNE ASSIGNMENTS, TO REMINGTON TYPEWRITER COMPANY, OF ILION, NEW
YORK, A CORPORATION OF NEW YORK.

TYPE-WRITING MACHINE.

1,206,854.

Specification of Letters Patent.

Patented Dec. 5, 1916.

Application filed April 6, 1915. Serial No. 19,470.

To all whom it may concern:

Be it known that we, HUBBARD N. JOSLEYN and JOHN W. KOERNER, citizens of the United States, and residents of Syracuse, in 5 the county of Onondaga and State of New York, have invented certain new and useful Improvements in Type-Writing Machines, of which the following is a specification.

Our present invention relates principally 10 to type bar mechanism for typewriting machines and its main object is to provide an improved construction of type bar and mounting for the same.

To the above and other ends our invention 15 consists in the features of construction, combinations of devices and arrangements of parts hereinafter described and particularly pointed out in the claims.

In carrying out our invention we provide 20 for a cheap construction of type bar and mounting by making the type bars of sheet metal and mounting them on a slotted support or segment on a common fulcrum or wire. One disadvantage in prior constructions 25 of this general nature has been that in order to dismount or remove one type bar it was necessary to dismount or disturb all the other type bars because the whole set of type bars have a common support. Also 30 there was the further disadvantage that the bearings became rapidly defective by reason of the sharp cutting edge of the sheet metal type bar grinding into the fulcrum wire at its point of connection therewith. These 35 disadvantages are avoided in our new and improved construction by providing an individual bearing sleeve for each type bar, said bearing sleeve not having the tendency to cut into the fulcrum wire to the same extent as the sheet metal type bar itself, and further by providing a detachable connection 40 between the type bar and its bearing sleeve so that the type bar may readily be removed from the common fulcrum or pivot device and replaced either by itself or by another type bar without disturbing the 45 other type bars of the set. The present construction is comparatively inexpensive and has been found in practice to be quite efficient 50 both in respect to efficiency of operation and in the readiness and facility with which the parts may be assembled and disassembled.

Our invention will be described in detail in connection with the accompanying drawings wherein—

Figure 1 is a side elevation of a type action embodying our present invention. Fig. 2 is a fragmentary front elevation, partly in section, of a type bar segment embodying 60 said invention. Fig. 3 is a fragmentary enlarged front elevation illustrating the type bar mounting. Figs. 4, 5 and 6 are fragmentary enlarged views of the pivot end portion of a type bar, Fig. 4 showing the 65 type bar detached, Fig. 5 showing the bar as it is being sprung in place over the associate sleeve, and Fig. 6 showing the type bar in place on its bearing sleeve.

Our present invention may be applied to 70 a typewriting machine like that shown in the co-pending application of Bond and Josley, Serial No. 18,987 filed April 3, 1915, which has matured into Patent 1,197,336, dated September 5, 1916, and wherein a segmental type bar support 1 is provided with a forwardly projecting curved portion 2 which is formed with a series of kerfs or slots 3, these slots being radial in respect to the printing point on the front face of a 80 platen 4. The portion 2 also has in its front face an arcuate slot 5 in which is seated a pivot device in the form of a segmental fulcrum or pivot wire 6, said wire being circular in cross section and being detachably 85 held in place by clips or fingers 7, said fingers being secured by screws 8 to the front face of the portion 2 near its ends and engaging at their free ends with the wire 6. This wire provides a common fulcrum for 90 all of the type bars 9 which are arranged in a segmental series or set. The type bars are preferably of sheet metal and each is secured to its free end with a type block 10 provided with two types, these types being 95 separately brought into use by shifting the segment in any suitable way as by the mechanism disclosed in said Bond and Josley application. A type rest 11 which normally supports the free ends of the bars is shiftable with the segment 1. Before describing 100 in detail the pivotal end and mounting of the type bar wherein our invention mainly resides, the actuating devices for the type bars may be briefly described. Each type 105 bar is connected by a detachable link 12 with

a sub-lever 13 which is pivoted at 14 to a key lever 15, the key levers being fulcrumed on a common fulcrum plate 16 and each provided with a key 17 and a restoring spring 18. The lower end of each sub-lever is fulcrumed at 19 to coöperate with a fixed abutment 20. These actuating devices or means are like those found in the Monarch machine.

10 The type bars are adapted to be separately forced or sprung into and out of place on the fulcrum wire so as not to disturb their fellows. Preferably instead of bearing directly on the wire 6 each type bar bears on a rotary bearing member or sleeve 21, there being a separate sleeve or collar for each type bar. These sleeves are preferably machined. They are of such width that they fit loosely into the slots 3 when strung along the fulcrum wire 6 on which they bear, and the construction is such that the sides of the slots 3 are engaged loosely by the sleeves which are thereby held in register with their slots and prevented 25 from lateral displacement lengthwise of the wire 6. In assembling the sleeves on the fulcrum wire it is preferable to insert the fulcrum wire 6 in one end of its seat or slot 5 and then to work it around gradually 30 lengthwise through said slot. Into each slot 3 the associate sleeve 21 is inserted by any convenient means as by a tweezer in position to be picked up by the fulcrum wire as it is pushed along. The fulcrum wire and the 35 sleeves having once been assembled on the segment 1, it will not be necessary to disturb them in putting on and removing the type bars. To this end each type bar at its pivot end is formed with a round or 40 circular opening 22 which will receive the associate sleeve 21 and frictionally grip or grasp the same. At the side of the opening 22 toward the type end of the type bar the type bar is formed with a long slit 45 or kerf 23 which connects with the opening 22, and at the opposite side from the kerf a comparatively wide mouth or entrance 24 to the opening 22 is provided, this mouth having flaring edges or sides 25. At 50 the outer ends the distance between the edges 25 is greater than the outer diameter of the sleeve 21 but at the inner ends of said edges where they join the opening 22 they are spaced apart slightly less than the sleeve 55 diameter. This requires that the jaws 26 and 27 formed in the type bar by the continuous opening made up of the slit 23, round opening 22 and mouth 24, shall be resilient or yielding so that the type bar 60 may be sprung into place on its sleeve. In Fig. 4 the type bar is shown detached. In mounting it in place the pivot end is passed rearward through the associate slot 3, the mouth 24 passing freely over the sleeve 21 65 until the narrow end of the mouth is ap-

proached when its sides will contact with the sleeve and will require that the bar be forced backward, causing the jaws 26 and 27 to separate or be sprung apart slightly until the mouth 24 has passed the sleeve 70 when the jaws will spring together and the sides of the opening 22 will grip the sleeve with sufficient friction to cause the sleeve and type bar to act as a single unitary device during turning movements of the type 75 bar. After the type bar has been thus assembled on its sleeve it is only necessary to connect its link 12 with the sub-lever 13 to make the bar ready for actuation by its key lever. In removing a type bar its link 80 is first detached from its sub-lever and then the type bar is pulled off either by hand or by the aid of pliers, the jaws being thus forced apart sufficiently to permit the bar to be pulled off its sleeve 21. 85

It will be observed that by our present invention we provide a fulcrum wire having individual type bars fulcrumed thereon, each type bar having means for affording a removal of the type bar singly from said wire 90 without disturbing the other type bars or the wire; that the type bar may be sprung on its pivot device or fulcrum wire; that preferably between the pivot device and the type bar is interposed a bearing member or 95 sleeve which is rotatable on the pivot device and on which the type bar is directly sprung, the type bar thereby having a pivotal connection with its pivot device or fulcrum wire; that the sleeve while rotatable on the pivot 100 device is held in its guide slot against substantial lateral movement; and that the type bar is guided by the guide slot or radial slot and has a fixed relationship with its sleeve during printing movements, the type 105 bar and sleeve acting as a single rigid member or device.

Preferably a center guide (not shown) is provided for coöperating with the type bars at or near the printing point. 110

Various changes may be made without departing from our invention.

What we claim as new and desire to claim by Letters Patent, is:—

1. In a typewriting machine, the combination of a fulcrum wire, individual type bars fulcrumed thereon, key controlled actuating devices for said type bars, and means for providing a bearing for the type bar that completely surrounds the pivot wire 115 and for affording a separate removal of said type bars from said wire without disturbing the other type bars or the fulcrum wire. 120

2. In a typewriting machine, the combination of a round fulcrum, a plurality of members rotatable thereon, and key operated type bars each frictionally held on one of said members. 125

3. In a typewriting machine, the combi- 130

nation of a pivot device, a sleeve rotatable thereon, a type bar sprung on said sleeve, and means for actuating said type bar.

4. In a typewriting machine, the combination of a pivot device, a slotted guide by which said device is mounted, a sleeve rotatable on said pivot device but held by the slot in said guide from lateral movement, a type bar sprung on said sleeve, said type bar being guided by said slot and having a fixed relation with said sleeve during printing movements, and means for actuating said type bar.

5. In a typewriting machine, the combination of a type bar support provided with radial slots, a pivot wire secured to said support, sleeves rotatable on said wire and each engaged in one of said slots, a set of type bars each sprung on one of said sleeves, and means for actuating said type bars.

6. In a typewriting machine, the combination of a pivot, a sleeve rotatable thereon, a type bar having spring jaws for gripping said sleeve, whereby the type bar and sleeve may be detachably connected, and means coöoperating with said type bar to turn said type bar and said sleeve as a single rigid member.

7. In a typewriting machine, the combination of a pivot, a slotted guide on which said pivot is mounted, a sleeve rotatable on said pivot, said sleeve being loosely engaged by the sides of the slot in said guide, a type bar having spring jaws detachably gripping said sleeve, said type bar being guided by said slot, and means for actuating said type bar, said type bar and said sleeve turning as a single device on said pivot.

8. In a typewriting machine, the combination of a type bar support provided with radial slots, a pivot wire releasably fixed to said support, sleeves rotatable on said wire, each sleeve loosely engaging one of said slots, type bars seated in said slots and each type bar having spring jaws detachably gripping one of said sleeves, and means for actuating said type bars, each type bar and its associate sleeve turning as a single device on said pivot wire.

50 9. In a typewriting machine, the combination of a pivot device, a plurality of machined sleeves loosely mounted on said pivot

device, sheet-metal type bars each frictionally connected to one of said sleeves, and means for separately actuating said type bars.

10. In a typewriting machine, the combination of a support provided with a slot, a pivot fixed to said support, a sheet metal type bar received in said slot, and a machined sleeve loosely mounted on said pivot and controlled by the sides of said slot, said type bar having spring jaws which frictionally engage said pivot.

11. In a typewriting machine, the combination of a pivot, a sleeve loosely mounted thereon, a type bar provided with an opening to fit over said sleeve, and a flaring mouth connected with said opening, the sides forming said flaring mouth being relatively yieldable.

12. In a typewriting machine, the combination of a pivot, a sleeve loosely mounted thereon, a type bar provided with an opening to fit over said sleeve, and a flaring mouth connected with said opening, the sides forming said flaring mouth being relatively yieldable, the type bar being slit at the side of said opening diametrically opposite said flaring mouth.

13. In a typewriting machine, the combination of a pivot, a sleeve loose thereon, and a sheet metal type bar provided with a round opening to fit over said sleeve, the sides of the type bar being slit or cut at diametrically opposite sides of said opening forming resilient jaws.

14. The combination of a pivot, a sleeve loose thereon, and a sheet metal type bar provided with a round opening to fit over said sleeve, the type bar having a narrow slit at one side of said opening and having a mouth at the opposite side of said opening wider at one end than the diameter of said sleeve.

Signed at Syracuse, in the county of Onondaga and State of New York, this 3d day of April, A. D. 1915.
